UNITED STATES PATENT OFFICE

ROBERT F. JONES, OF WASHINGTON, DISTRICT OF COLUMBIA

DESIGN FOR AN ASH RECEIVER

Application filed July 19, 1932. Serial No. 44,375. Term of patent 14 years.

To all whom it may concern:

Be it known that I, ROBERT F. JONES, a citizen of the United States, residing at Washington, in the District of Columbia, have invented a new, original, and ornamental Design for an Ash Receiver, of which the following is a specification, reference being had to the accompanying drawing, forming a part thereof.

In the drawing:

Fig. 1 is a side elevation of an ash receiver,

showing my new design, the broken lines illustrating the contour as observable in an embodiment of the design made of transparent material.

Fig. 2 is a plan view, showing one-half the top of an ash receiver embodying my design.

I claim:

The ornamental design for an ash receiver, as shown and described.

ROBERT F. JONES.
